UNITED STATES PATENT OFFICE.

EARL W. DOTTEN, OF DE GRAFF, MINNESOTA.

DITCHING-MACHINE.

1,264,906.

Specification of Letters Patent.

Patented May 7, 1918.

Application filed September 17, 1917. Serial No. 191,771.

To all whom it may concern:

Be it known that I, EARL W. DOTTEN, a citizen of the United States, residing at De Graff, in the county of Swift and State of Minnesota, have invented certain new and useful Improvements in Ditching-Machines, of which the following is a specification, reference being had therein to the accompanying drawing.

10 This invention consists of certain new and useful improvements in ditch digging machines and relates especially to such machines known as dry land ditching machines and by which expression is meant that the 15 machine is designed to operate on land instead of water as is sometimes the case.

The principal object of my present invention is to provide a machine of this character with the maximum stability and range 20 of operation in proportion to its weight.

One trouble in particular, well known to those versed in the art of dry land ditching, is that of successfully operating a dipper shovel against the face of a ditch while supported upon the berms of the ditch.

25 The chief danger accompanying such an operation is that of the caving in of the sides of the ditch from unequal pressure due to the swinging from side to side of the dipper and being obliged to extend the loaded dipper the full length of the boom in order to properly discharge the same upon the dump, such booms sometimes being used that are eighty or more feet in length. To 30 overcome such difficulties and objections to the present form of ditching machines forms another object of this invention.

Other objects and advantages of the novel construction and combination of parts will 40 appear as hereinafter set forth and particularly pointed out in the claims.

Referring to the accompanying drawings forming part of this application and in which like reference characters indicate like 45 parts:

Figure 1 is a top plan view of the improved ditching machine as it would appear in the act of digging a ditch.

Fig. 2 is a vertical central sectional view 50 of the vehicle portion of the mechanism illustrating certain parts thereof in elevation,

Fig. 3 is a transverse sectional view showing in elevation the laterally discharging 55 conveyer and berm cleaners, and,

Fig. 4 is a fragmental elevation of the front wheel shaft mounting mechanism.

In the embodiment of my invention here illustrated, 1 represents a working platform or deck supported upon four large fabricated wheels 2 and 3 in the front and 4 and 5 in the rear, comprising a portable vehicle.

The deck 1 prefer to have carried upon a suitable iron bar frame 6, composed of such as channel bars, I beams or angles and to be, 65 in general plan, substantially rectangular in shape.

The rear wheels 4 and 5 are supported upon a single axle 7 and are placed in the extreme rear corners of the frame 6 and the front wheels 2 and 3 are placed in the forward corners of the frame but spaced a distance in from the sides and ends thereof to admit of a certain amount of swiveling for turning of the vehicle as will be described 75 later.

A large polygonal central opening or hatchway 8 is formed through the deck 1 and in which hatchway the ditching shovel is operated.

80 An arcuately shaped track 9 is supported centrally above the hatchway 8 upon any form of suitable structure such as the uprights 10 and 11. The track 9 may be of any desired structure but I have shown as a 85 convenient and practical form, an upright member, indicated by the numeral 9, to the inner wall of which are fixed two vertically spaced angle bars, 12—12, which form the guide rails of the track.

80 Figure 13 represents the dipper carrying boom which is pivotally mounted as at 14 upon the deck 1 adjacent the rear edge of the hatchway 8; said pivotal point being that from which the arcuate track 9 is described.

95 The opposite or free end of the boom 13 is swingingly supported upon the track 9 by means of the roller 50, pivotally carried upon the extreme end of the boom and operative intermediate of the two angle bars 100 12—12, it normally resting upon the lowermost angle bar.

90 This boom is of the type known as a split boom, and carries, intermediate of its two halves, the dipper stick 15, which is controlled and operated in the usual manner, there being a crowding engine 16 mounted upon the boom for assisting in the operation.

I have illustrated the line 17, which is attached to the dipper 18 as leading therefrom 100

up to and over a sheave 19 in the upper end of the boom and thence downward to and between the sister sheaves, 20—20, to the winding drum 21, the sister sheaves being 5 directly over the pivotal point 14 of the boom to admit of the swinging of the boom without materially altering the draft upon the line from the drum.

The drum 21 is mounted upon the trans- 10 verse shaft 22, rotatably carried in any desired manner upon the deck 1 and which derives its power from the internal combustion engine or other suitable motor 23.

At either side of the drum 21 and mounted 15 upon and adjacent each end of the shaft 22 is a swinging drum 24, each having a line 25 attached to the side of the boom, whereby the boom may be swung from side to side at the will of the operator as is obvious. It 20 is not deemed necessary to illustrate the mechanism for the control of the drums 21 and 24 upon the line shaft 22 as such forms no part of my present invention and any one 25 of various forms of well known means for such operation may be employed.

Near each end of the shaft 22 and extending forwardly in respect to the vehicle is a short shaft 26, they communicating with the shaft 22 and being operated by suitable 30 miter gears as illustrated at 27.

The forward end of each shaft 26 carries a sprocket wheel 28, which, by means of suitable sprocket chains, operate the berm cleaners, each one of which comprises a driving 35 shaft 29 and a driven shaft 30, carrying suitable sprocket wheels for driving an endless chain or belt 31 for scraping and cleaning the upper surface of the berms to make a smooth track for the rear wheels of the 40 ditcher. Coarse brushes or other suitable scraping teeth may be attached to the chain or belt 31.

These berm cleaners are illustrated as being suspended from the frame of the chassis 45 and I prefer to suspend the same pivotally, as for example the outer portion 32 of the suspended frame being pivoted at 33 and the portion 34 at the inner end being pivoted upon its respective shaft 26, the lower 50 ends of both portions 32 and 34 of the suspended frame being pivoted upon the shafts 30 and 29 respectively. Thus a swinging motion in either direction of the berm cleaning belts will tend to raise them from the 55 ground, and, to hold same in any predetermined position desired, I provide inclined braces 35 extending from the ends of the shafts 30 to the uppermost inner corners of the suspended frame where they may be 60 fastened in any one of a series of holes 36 formed for the purpose in a transverse depending portion of the frame 6.

It is apparent that the berm cleaning belts are made to operate in a direction to 65 move the dirt therefrom outwardly from

the ditch and thus provide a clean and smooth passage way for the wheels of the ditcher.

Mounted upon the rear axle 7 of the vehicle is a large sprocket wheel 37 which is designed to be driven from the shaft 22 by means of a smaller sprocket 38 and a suitable chain surrounding said sprockets, the activity of the sprocket 38 being controlled in any desired manner as for instance by a 70 suitable manually controlled clutch mechanism indicated at 39. By this arrangement tractive power may be applied to the rear wheels 4 and 5 as they are rigidly fixed to the axle 7 and the machine thus propelled. 80

Just below and inside of the forward edge of the hatchway 8 is permanently fixed a short endless belt receiving platform 40, the belt being carried upon suitable rollers mounted upon shafts 41 and 42, the latter 85 being driven by a sprocket wheel 43 and a chain 44 from a suitable motor or engine 45 placed in any desired position upon the forward portion of the deck 1.

Below each shaft 41 and 42 is suspended 90 the inner and lowermost ends of laterally and upwardly extending endless conveyors 46, the specific construction of which does not enter into this invention and it is evident that a single one of such conveyors 95 may be employed in lieu of the pair and the one changed from one side of the ditcher to the other to meet requirements.

I have illustrated the outer ends of these conveyors as being suspended from suitable 100 masts 47, one for each conveyor and located upon the deck 1. By this arrangement the conveyors may be raised or lowered to suit circumstances and whereby the material taken from the ditch and received from the 105 central platform belt 40 may be piled to any desired height at the side of the machine.

When the ditcher is equipped with two of the conveyors 46 as illustrated, it is evident that by simply reversing the travel of 110 the platform belt 40 the excavated material may be delivered to either one of the conveyors 46 desired, it being understood that the excavating shovel 18 delivers the material upon the belt 40. A suitable inclined 115 apron 48 is positioned in front of the belt 40 to guide the material to the belt when discharged from the shovel.

The front wheels 2 and 3 of the vehicle are each placed in a hatchway 49 somewhat 120 larger than the plan dimension thereof to permit of the wheels being pivotally mounted for manipulation in turning the vehicle or causing it to travel in a curved direction.

The outer end of each axle 51 of such 125 wheels is pivotally mounted as at 52 within a suitable inwardly extending bracket 53 from each side of the frame 6. The opposite end of each axle is journaled in two adjacent bearings 54 and 55 formed integral with the 130

member 56, it having upon the upper side thereof an arcuately shaped rack 57 into which a correspondingly shaped beveled gear 58 meshes and by which the inner end 5 of the axle may be swung either one way or the other for changing the course of each respective wheel.

The bearing 55 is made rectangular in shape externally and is slidably mounted 10 within a suitable arcuately shaped section of channel bar 59 rigidly fixed to the frame 6 of the vehicle and which acts as a support and guide to the coöperating end of the axle.

I have shown the shaft 60 upon which the 15 beveled gears 58 are mounted as being a continuous shaft and operated centrally by means of a worm gear 61 and the coöperating worm upon a vertical hand operating shaft 62 provided with a hand wheel 63 whereby the vehicle is steered. By this arrangement it is evident that if the beveled gears 58, at both ends of the shaft 60 occur 20 upon the upper face of the arcuate racks 57 they will tend to travel in the same direction when operated by the gears which would cause the wheels 2 and 3 to oppose each other in turning action, thus it becomes necessary to operate one of the gears 58 against the under side of the rack as indicated in Fig. 1 of the drawing, such rack 57 being simply sufficiently elevated for the 25 purpose and having the teeth formed upon the lower side thereof instead of the upper, which will result in the wheels 2 and 3 turning harmoniously.

From the foregoing it is apparent that I 30 have devised a ditch digging machine in which a dipper shovel is used for forming the ditch, there being no mast whatever employed and no overhang of the dipper when loaded as the endless conveyors carry the excavated material out beyond the sides of the machine during a prolonged operation as compared to the discharge of the dipper 35 shovel as commonly used for such purposes, thus materially reducing the tipping stress upon the mechanism and consequent liability of caving in of the ditch walls.

Furthermore in this construction of machine where the weight is equally distributed upon four large wheels it is possible to use a shovel of much greater capacity than heretofore.

Having thus described my invention, what 40 I claim as new and desire to record by Letters Patent, is:

1. A ditching machine of the character described comprising in combination a wheeled vehicle having a flat working deck, 45 an open hatchway through approximately the center of the deck, an arcuately shaped track elevated above and extending transversely the hatchway, a boom having one end pivotally supported upon the deck adjacent the rear edge of the hatchway and the

opposite end swingingly supported in the arcuate track, a dipper shovel carried centrally of the boom and operative through the hatchway, and a laterally disposed endless conveyer adjacent the forward edge of 70 the hatchway for receiving the excavated material from the shovel and discharging it to one side of the machine.

2. A ditching machine of the character described comprising in combination a 75 wheeled vehicle having a flat working deck, an open hatchway through approximately the center of the deck, an arcuately shaped track above and extending transverse the hatchway, a support having one end pivotally mounted upon the deck adjacent the rear edge of the hatchway and the opposite end, swingingly supported in the arcuate track, ditch digging means carried by the support and operative through the hatchway and means for receiving the excavated material from the digger and discharging it 80 to one side of the machine.

3. The combination with a ditch digging machine of the character described comprising a self propelled vehicle having an open central hatchway therein, of a boom pivotally supported at one end adjacent the rear edge of the hatchway and at the opposite end swingingly supported above the 90 hatchway, a dipper pivotally carried by the boom and operative through the hatchway and means for receiving the excavated material from the shovel and discharging it to 95 one side of the machine.

4. The combination with a ditch digging machine of the character described, comprising a four wheeled vehicle and means for digging a ditch intermediate of the wheels of the vehicle, of berm cleaners 105 mounted in front of the rearmost wheels of the vehicle whereby the leavings of the digging means on the berms of the ditch are removed.

5. The combination with a machine of the 110 character described, comprising a four wheeled vehicle and means for digging a ditch intermediate of the wheels of the vehicle, of operative berm cleaners mounted in front of the rearmost wheels of the vehicle 115 and means whereby the berm cleaners are simultaneously operated with the advancement of the vehicle whereby the leavings of the digging means on the berms of the ditch are removed therefrom as the machine is 120 advanced.

6. The combination with a four wheeled vehicle having a flat working deck with an open hatchway through the center thereof, an arcuate track above and transverse the 125 hatchway, a shovel carrying boom pivotally mounted upon the deck at one end and swingingly supported upon the track at the opposite end, of a transversely disposed rotatable power shaft at the rear of the piv- 130

otal end of the boom and intermediate of the rear wheels of the vehicle, means operated by the shaft for operating the shovel carried by the boom, means operated by the shaft for swinging the boom laterally, a shaft at each end of the first mentioned shaft, operated thereby and extending to a point adjacent the front of the rear wheels of the vehicle, and means at said forward end of each shaft for operating a berm cleaner in front of each respective rear wheel of the vehicle substantially as described.

7. The combination with a four wheeled vehicle of the character described including a pivotally mounted swinging dipper carrying boom and endless belt berm cleaners in front of the rear wheels of the vehicle, of means intermediate of said rear wheels for operating the shovel, the boom, the berm cleaners and the vehicle simultaneously or some of said parts independently.

8. A ditching machine of the character described, comprising a substantially rectangular shaped chassis frame, four large wide wheels mounted in the four corners of the frame, a driving axle nonrotatably fixed

to and upon which the rear wheels are mounted, a flat working deck upon the chassis frame, openings through the deck at the four corners of same in which the wheels are mounted, the openings in the forward corners being considerably larger than the forward wheels and in which the latter are rotatably and pivotally mounted, means for changing the direction of the forward wheels for steering the machine, a large open hatch through the deck and positioned centrally intermediate of the four wheels, ditch digging means within the hatch and supported upon the deck, means supported by the deck for receiving the excavated material from the digging means and conveying it to one side of the machine, and means for cleaning the berms of the ditch in front of the rear wheels of material left thereupon by the ditch digging means substantially as and for the purpose described.

In testimony whereof I hereunto affix my signature in the presence of two witnesses.

EARL W. DOTTON.
